MULTIPLIER PHOTOTUBE CIRCUIT

John R. Parsons, Pennsauken, N. J., assignor, by mesne assignments, to the United States of America as represented by the Secretary of the Army

Application May 3, 1955, Serial No. 505,662

4 Claims. (Cl. 250—207)

This invention relates generally to multiplier phototube circuits, and more particularly to a light detecting circuit comprising means to stabilize it against variations in the intensity of the exciting light source, and against variations in the operating voltage. While neither specifically nor exclusively limited thereto, the multiplier phototube circuit of the present invention is particularly useful in a portable instrument of the type employed to detect changes in color of a sensitive chemical indicator when affected by a gas or vapor.

It has been proposed to stabilize multiplier phototube circuits against unwanted changes in the intensity of the exciting light source, and against variations in the voltage of the voltage source by varying the dynode voltages applied to the dynodes of the multiplier phototubes to vary their gain accordingly. In such circuits, at least two multiplier phototubes have to be matched carefully because their operating characteristics have to be similar to each other over substantially the entire range of the phototubes' operating characteristic curves. When the gains of the multiplier phototubes are varied to compensate for the aforementioned changes, the sensitivities of the multiplier phototubes vary. Thus, multiplier phototube circuits that are compensated by varying the gains of the multiplier phototubes have an output voltage that will vary with respect to a reference voltage even in the absence of an actual light signal to be measured. Hence, such a varying output voltage cannot be used to operate a subsequent indicating circuit at its optimum transconductance point.

Accordingly, it is a principal object of the present invention to provide an improved multiplier phototube circuit that will be stabilized against variations in operating voltages, and in unwanted variations in the intensity of the light source, and yet provide an output voltage that is fixed with respect to a reference voltage, in the absence of an actual signal.

Another object of the present invention is to provide an improved multiplier phototube circuit, employing multiplier phototubes that are always operated at a constant gain, and having means to stabilize it against the aforementioned variations.

A further object of the present invention is to provide an improved multiplier phototube circuit employing multiplier phototubes that need not be matched, and employing means to operate an output circuit in a highly efficient manner.

It is still a further object of the present invention to provide an improved multiplier phototube circuit employing phototubes that always operate with a fixed gain and have an output voltage that is held substantially constant with respect to a reference voltage in the absence of actual signals to be detected.

A still further object of the present invention is to provide an improved multiplier phototube circuit that is relatively simple in construction and operation, economical to manufacture and yet highly efficient in use.

2

These and, perhaps, further objects of the present invention are attained in an improved multiplier phototube circuit having at least two multiplier phototubes. Each of the multiplier phototubes has a photocathode, 5 one or more intermediate dynodes and an anode. The photocathodes and the dynodes of the multiplier phototubes are connected in parallel to each other, respectively, and the dynodes are provided with operating voltages from a voltage divider connected across a source of regulated relatively high unidirectional voltage. Thus, the gain of each of the multiplier phototubes is maintained constant within the range of normal operating conditions. Means are provided to maintain each of the anodes of each of the multiplier phototubes at a fixed voltage 10 with respect to a reference voltage, such as ground, in the absence of an actual signal to be detected. To this end, a first circuit comprising a first variable impedance tube and a cathode resistor, and a second circuit comprising a second variable impedance tube and an anode resistor are connected in parallel between ground and a source of relatively low unidirectional voltage. The anode of the second variable impedance tube is connected to the grid of the first variable impedance tube, and the cathode resistor is connected to the anode of each multiplier phototube through a separate load resistor. The anode of one of the multiplier phototubes, hereinafter referred to as a reference multiplier phototube, is connected to the grid of the second variable impedance tube. The anode of the other of the multiplier phototubes, hereinafter called the sampling multiplier phototube, comprises 15 the output of the sampling multiplier phototube. Similar variations in the intensity of the exciting light source sensed by both the reference and the sampling multiplier phototubes, will produce no change in the anode voltage 20 of the sampling multiplier phototube with respect to ground. Also, changes in the voltage source, within a range of normal operation, will not produce any change in the anode voltage of the sampling multiplier phototube. A change in the output voltage, that is, the anode voltage, of the sampling multiplier phototube will result 25 only when the sampling multiplier phototube receives an actual light signal. An actual light signal as used herein refers to a change in the light intensity caused by an event that is to be detected, such as the change in color 30 of a chemically treated indicator material in the presence of a gas.

The novel features of the invention, as well as the invention itself, both as to its organization and method of operation, will be understood in detail from the following description when considered in connection with the accompanying drawing, the single figure of which is a schematic illustration of a multiplier phototube circuit in accordance with the present invention.

Referring now to the drawing, there is shown a multiplier phototube circuit comprising a reference multiplier phototube 10 and a sampling multiplier phototube 12. The photocathodes 14 and 16 of the multiplier phototubes 10 and 12 are connected to each other and to a negative terminal 18 for applying a relatively high unidirectional negative voltage, say —1,000 volts, thereto. Each of the multiplier phototubes 10 and 12 are provided with one or more dynodes. The dynodes 20–22 of the reference multiplier phototube 10 are connected in parallel with the dynodes 23–25 of the sampling multiplier phototube 12, respectively, and to successive points along a voltage divider 26 for the purpose of providing fixed operating voltages thereto. The voltage divider 26 is connected between the terminal 18 and a point of reference voltage, such as ground. While only three dynodes are shown for each of the multiplier phototubes 10 and 12, it is understood that the number of dynodes employed will be determined by the sensitivity desired.

Means are provided to maintain the gain of each of the multiplier phototubes constant. To this end, regulated voltage means are provided between the terminal 18 and ground to maintain the voltage across the voltage divider 26 substantially constant. Operating voltages are provided by a blocking oscillator circuit comprising, for example, a triode tube 30. A source of unidirectional voltage, such as a 24 volt battery 32, has its positive terminal connected to the anode of the tube 30 through a section 34 of an autotransformer 36. The anode of a tube 30 is connected to the anode of a rectifier diode 38 through a section 40 of the autotransformer 36 and a capacitor 42. The cathode of the diode 38 comprises a filament connected to ground and to a source of suitable operating voltage (not shown), in a manner well known in the art. The filament and heater connections, of the tubes used herein, are not shown because they are well known in the art, and because it is desired to maintain the diagram as simple and readable as possible. The negative terminal of the voltage source 32 is connected to the cathode of the tube 30, and to ground. The grid of the tube 30 is connected to ground through a section 44 of an autotransformer 46 wound on the same core as the autotransformer 36. The section 44 of the autotransformer 46 is also connected to ground through the series circuit comprising a section 48 of the autotransformer 46, a rectifier 50 and a capacitor 52.

The capacitor 42 is connected to the cathode of a cold cathode rectifier tube 54. The anode of the rectifier tube 54 is connected to the output terminal 18 through a filter resistor 56. Each end of the filter resistor 56 is connected to ground through separate capacitors 58 and 60 for filtering purposes. A voltage regulating tube 62, of the gas type, is connected between the terminal 18 and ground for the purpose of maintaining the unidirectional voltage therebetween substantially constant.

It will now be understood that the tube 30 is connected in a blocking oscillator circuit for converting the relatively low battery voltage 32 into an alternating voltage, and rectifying this alternating voltage by the rectifiers 38 and 54 to provide a relatively high unidirectional voltage between the output terminal 18 and ground. A voltage of about -1,000 volts, with respect to ground, is obtained at the negative terminal 18 in the following manner: Current will flow through the tube 30 until the saturation point is reached. Upon saturation, the grid of the tube 30 will be driven sufficiently negative so that conduction through the tube 30 will be cut off. This causes a collapse of the magnetic fields about the autotransformers 36 and 46, and induces a stepped up voltage thereacross. The grid of the tube 30 will now approach ground potential and cause current to flow through the tube 30 again, repeating the cycle. The autotransformer 46, the capacitor 42, and the rectifiers 38 and 54 function in the nature of a voltage multiplier circuit to produce a relatively high voltage across the capacitor 42. This voltage is filtered by the resistor-capacitor network 56, 58 and 60 in the usual manner, regulated by the voltage regulating tube 62, and applied between the terminal 18 and ground.

The alternating voltage induced in the autotransformer 46 is rectified by the rectifier 50, and the rectified voltage is impressed across the capacitor 52. Thus, a unidirectional voltage that is positive with respect to ground may be obtained at a positive terminal 64, connected between the rectifier 50 and the capacitor 52. The unidirectional voltage appearing between the positive terminal 64 and ground is relatively low, say 100 volts, compared to the unidirectional voltage between ground and the negative terminal 18.

The blocking oscillator, comprising the tube 30 and its associated circuitry, may be looked upon as a power supply for converting the unidirectional voltage source 32 into a relatively low unidirectional voltage, say 100

volts, between the positive terminals 64 and ground, and into a relatively high negative unidirectional voltage, say -1,000 volts, between ground and the negative terminal 18.

Means are provided to maintain the anodes of the multiplier phototubes 10 and 12 at a fixed voltage with respect to ground when the light signals received by the multiplier phototubes 10 and 12 are the same. To this end, there is provided a regulating circuit comprising a first variable impedance tube, such as a triode tube 66, and a second variable impedance tube, such as a triode tube 68. The anode of the tube 66 is connected to the positive terminal 64, and the cathode thereof is connected to ground through a cathode resistor 70. The anode of the triode tube 68 is connected to the positive terminal 64 through an anode resistor 72, and the cathode thereof is connected to ground. The cathode of the tube 68 is of the filament type; the source of filament voltage being omitted for purposes of clarification. The anode of the tube 68 is connected to the grid of the tube 66. The cathode of the tube 66 is connected to the anodes of the multiplier phototubes 10 and 12 through the separate anode resistors 74 and 76, respectively. The grid of the tube 68 is connected to the anode of the reference multiplier phototube 10.

The multiplier phototubes 10 and 12 are physically disposed to receive light from adjacent chambers 80 and 82, respectively. Appropriate light directing shades (not shown) may be used. The dashed lines 84 and 86 represent the direction of light from the chambers 80 and 82 to the multiplier phototubes 10 and 12, respectively. The chambers 80 and 82 are formed with a light transparent filter 88 so that reflected light from the chambers 80 and 82 may pass to the multiplier phototubes 10 and 12. A strip of chemically treated indicator material 90 is disposed at the bottom of the chambers 80 and 82 in a manner whereby reflected light therefrom will pass through the filter 88 and onto the phototubes 10 and 12. The indicator material 90, for example, may be similar to litmus paper whose color is dependent upon the alkalinity or acidity of vapors to which it is subjected. It will be understood that the chambers 80 and 82 are illuminated equally by the same light source (not shown) so that the light reflected from the indicator material 90 to the phototubes 10 and 12 will be the same when the indicator material 90 is unaffected by any vapor or gas.

The chamber 82 is formed with an opening 92 therein for the purpose of allowing a gas or vapor to enter whereby to affect the indicator material 90 within the chamber 82 only. It will also be understood that the chamber 80 is sealed in a manner whereby no gas to be detected can enter therein. Hence, changes in the intensity of light reflected from the indicator material 90, due to chemical changes, aging, temperature and/or factors other than the presence of a gas or vapor to be detected, will affect each of the phototubes 10 and 12 in a similar manner. An actual signal, due to the presence of a gas or vapor in the chamber 82 only, will cause the portion of the indicator material 90 within the chamber 82 to change color in a manner whereby the signal received by the sampling phototube 12 will be different from that received by the reference phototube 10.

The output of the sampling phototube 12 is connected to the grid of a triode tube 94. The tube 94 and a triode tube 96 are connected in a bridge circuit 98 that functions as an indicating means to indicate the presence of a gas or vapor to be detected. The triode tubes 94 and 96 may be enclosed in the same envelope, as a duotriode. The anodes of the tubes 94 and 96 are connected to a source of suitable operating voltage, such as the voltage available at the positive output terminal 64. The cathodes of the tubes 94 and 96 are connected to ground through separate cathode resistors 100 and 102. An indicating device, such as a voltmeter 104, is connected

between the cathodes of the tubes 94 and 96. The grid of the tube 96 is connected to a suitable point on the cathode resistor 102 in order to fix its bias and to cause the tube 96 to conduct uniformly.

In order to derive an indication on the voltmeter 104, under conditions of maximum sensitivity, the tube 94 must be operated at its optimum transconductance point. It is an important feature of the present invention to maintain the grid of the tube 94 at a predetermined fixed potential with respect to ground, in the absence of an actual signal, due to the presence of a gas or vapor, so that the tube 94 will operate at its optimum transconductance point.

The operation of the multiplier phototube circuit, in accordance with the present invention, will now be described: Let it be assumed that because of aging and/or temperature changes, for example, there is a similar change in the indicating material 90 within the chambers 80 and 82 so that a similar change in the intensity of light is sensed by the reference multiplier phototube 10 and by the sampling multiplier phototube 12. It will be understood that the gain of each of the multiplier phototubes 10 and 12 is maintained substantially constant because the voltage across the voltage divider 26 is maintained constant by the voltage regulator tube 62. If, for example, it is assumed now that the reflected light from the indicator material 90 is decreased by these changes, there will be a decrease in the conduction through the reference multiplier phototube 10, and through the sampling multiplier phototube 12, and the anode voltages thereof will tend to go more positive. This positive-going signal will cause the grid of the tube 68 to go positive, and to provide a negative-going voltage at the grid of the tube 66. Because of the cathode follower action of the tube 66, this negative-going voltage is applied to the anodes of the phototubes 10 and 12 through their anode resistors 74 and 76, respectively. Thus, the original tendency of the anodes of the phototubes 10 and 12 to go positive are offset by this latter negative-going voltage. It will also be understood that any tendency for the anodes of the phototubes 10 and 12 to go negative, because of similar light signals received, will result in a positive-going signal at the cathode of the tube 66 that will tend to compensate for these changes.

It will also be noted that any change in the operating voltage of the tubes 66 and 68 will be compensated in a manner whereby the anode voltages of the phototubes 10 and 12 will tend to remain substantially constant, in the absence of a signal to be detected. Let it be assumed, for example, that the anode voltage on the tubes 66 and 68 decreases. The cathode voltage of the tube 66 will decrease and cause the grid of the tube 68 to decrease in voltage. This will result in a positive-going voltage at the anode of the tube 68. This positive-going voltage is now applied to the grid of the tube 66, and conduction therethrough will now increase. An increased conduction through the tube 66 will now provide a positive-going signal at the cathode thereof. Thus, a tendency for the operating voltage across the tubes 66 and 68 to vary results in a set of conditions whereby the voltage across the cathode resistor 70 is maintained substantially constant.

The grid bias for the tube 94, in the absence of a signal due to a gas or a vapor to be detected by the sampling multiplier phototube 12 will be maintained at a fixed voltage whereby the tube 94 of the bridge circuit 98 will operate at its optimum transconductance point. It will be understood that the bias required for such optimum operation is obtained from the anode voltage of the tube 12. Let it now be assumed that the vapor or a gas to be detected enters the opening 92 whereby the portion of the indicator material 90 within the chamber 82 changes in color. Let it be assumed, also, that as a result of this change in color, the intensity of light

sensed by the sampling multiplier phototube 12 is decreased. This will result in decreased conduction through the multiplier phototube 12, and the anode voltage of the sampling multiplier phototube 12 will tend to go positive. The positive-going voltage is applied to the grid of the tube 94, thereby increasing conduction therethrough and raising the voltage at the cathode thereof. Since the grid bias for the tube 96 is fixed and conduction therethrough is steady, the meter 104 will indicate any difference in voltage between the cathodes of the tubes 94 and 96. By maintaining the grid of the tube 94 at its optimum transconductance point in the absence of an actual signal, the occurrence of an actual signal due to a gas or vapor, will provide a maximum amplification within the tube 94, thereby increasing the overall sensitivity of the circuit.

What is claimed is:

1. A multiplier phototube circuit comprising a pair of multiplier phototubes each having an anode, a photocathode and one or more intermediate dynodes, parallel connections between said photocathodes and said dynodes of said pair of multiplier phototubes, a point of reference voltage, means including a voltage divider to apply a source of regulated unidirectional voltage between each 20 of said photocathodes and said point of reference voltage, means connecting each of said dynodes to selected points on said voltage divider to fix the voltage at said dynodes with respect to said point of reference voltage, a pair of resistors connected to each other and between 25 the anodes of said pair of multiplier phototubes, a third resistor connected between the common junction of said pair of resistors and said point of reference potential, and means including said pair of resistors and said third resistor to maintain said anodes at a substantially constant voltage with respect to said point of reference potential when light signals received by each of said multiple phototubes are the same.
2. A multiplier phototube circuit comprising a pair of multiplier phototubes each having an anode, a photocathode and one or more intermediate dynodes, parallel connections between said photocathodes and said dynodes of said pair of multiplier phototubes, a point of reference voltage, means to apply a source of regulated unidirectional voltage between each of said photocathodes 40 and said point of reference voltage, means connecting each of said dynodes to said regulated voltage applying means to fix the voltage of said dynodes with respect to said point of reference voltage, a pair of resistors connected to each other and between the anodes of said pair 45 of multiplier phototubes, a first and a second tube each having at least an anode, a grid and a cathode, a cathode resistor connected between said cathode of said first tube and said cathode of said second tube, an anode resistor connected between said anode of said first tube and said anode of said second tube, means to apply an 50 operating voltage between said anode of said first tube and said cathode of said second tube, said cathode of said second tube being connected to said point of reference voltage, means connecting said cathode of said first tube to the common junction of said pair of resistors; means connecting the anode of said second tube to the 55 grid of said first tube, and means connecting the grid of said second tube to an anode of one of said pair of multiplier phototubes.
3. A multiplier phototube circuit comprising first and second multiplier phototubes each having a photocathode, one or more intermediate dynodes and an anode, a point of reference voltage, a voltage divider connected between said photocathodes and said point of reference voltage, 60 means connecting said dynodes to points on said voltage divider, means for applying a source of fixed voltage across said voltage divider, a pair of resistors connected to each other and between said anodes, a first tube having an anode, a grid and a cathode, a cathode resistor connected between said cathode of said first tube and

said point of reference voltage, a second tube having an anode, a grid and a cathode, said cathode of said second tube being connected to said point of reference voltage, a load resistor connected between the anode of said first tube and the anode of said second tube, means to apply a source of unidirectional voltage between said anode of said first tube and said point of reference voltage, said cathode of said first tube being connected to the common junction of said pair of resistors, said anode of said second tube being connected to said grid of said first tube, and means connecting said grid of said second tube to said anode of said first multiplier phototube.

4. A multiplier photo circuit, adapted to compensate for variations in the intensity of an exciting light source, comprising a reference multiplier phototube and a sampling multiplier phototube, each of said phototubes having a photocathode, one or more dynodes and an anode, a point of reference voltage, means to apply a fixed voltage between said photocathodes and said point of reference voltage, said last-mentioned means comprising means to apply fixed voltages to said dynodes with respect to said point of reference voltage, means to maintain each

10

15

20

of said anodes at a constant voltage with respect to said point of reference voltage comprising a first and second tube each having at least an anode, a grid and a cathode, an anode load resistor connected between the anode of said first tube and the anode of said second tube, a cathode resistor connected between said cathode of said first tube and said cathode of said second tube, said anode of said second tube being connected to said grid of said first tube, a pair of resistors, said cathode of said first tube being connected to said anode of said reference multiplier phototube and to said anode of said sampling multiplier phototube through a separate one of said pair of resistors, respectively, and said grid of said second tube being connected to the anode of said reference multiplier phototube.
